UNITED STATES PATENT OFFICE.

STIRLING MOORE, OF PHILADELPHIA, PENNSYLVANIA.

DESIGN FOR A BRACKET.

No. 39,962.

Specification for Design.

Patented May 4, 1909.

Application filed February 17, 1909. Serial No. 478,526. Term of patent 7 years.

To all whom it may concern:

Be it known that I, STIRLING MOORE, a subject of the King of Great Britain, residing at Philadelphia, in the county of Philadelphia and State of Pennsylvania, have invented a new, original, and ornamental Design for Brackets, of which the following is a specification, reference being had to the accompanying drawing, forming part thereof.

The figure is a front elevation of a bracket, showing my new design.

I claim:

The ornamental design for a bracket, as shown.

STIRLING MOORE.
